UNITED STATES PATENT OFFICE.

WILLIAM W. BUTLER, OF DECATUR, ILLINOIS.

COOLING-CASE FOR SODA-FOUNTAINS.

No. 802,969.

Specification of Letters Patent.

Patented Oct. 31, 1805.

Application filed July 1, 1904. Serial No. 214,859.

To all whom it may concern:

Be it known that I, WILLIAM W. BUTLER, a citizen of the United States, residing at Decatur, in the county of Macon and State of Illinois, have invented certain new and useful Improvements in Cooling-Cases for Soda-Fountains, of which the following is a specification, reference being had therein to the accompanying drawings.

10 This invention relates to an improvement in cooling-cases for soda-water fountains; and the object of the invention is the construction of a case of this character which will be comparatively simple in construction, at all times 15 keep the aerated water-holders and syrup-jars cool, and which will permit the operator to have access to said holders and jars at all times.

In the drawings accompanying this specification, wherein a preferable embodiment of 20 my invention is shown and wherein like numerals of reference refer to similar parts in the several views, Figure 1 is a vertical cross-section of my improved cooling-case. Fig. 2 is a horizontal section of the same, and Fig. 25 3 is a longitudinal section.

Referring now more particularly to the drawings, A indicates the lower portion of the cooling-case, and B the upper portion of the same, which is detachably secured thereon. 30 The upper portion B of the case is somewhat smaller in cross-section than the lower portion A, and the latter portion is formed with a flat inwardly-extending ledge A' along its two sides and front. The inner edges of the 35 ledge A' and the rear edge of the lower section A are provided with upwardly-extending tongues, which are adapted to cooperate with grooves s', formed on the lower side of the upper section B to form an interlocking joint 40 between the two sections.

C is a horizontally-disposed partition which is secured in the lower section A at some little distance from the top thereof, the portion or space above said partition constituting 45 the lower portion of an ice-receptacle and the portion below a cooling-chamber in which extra bottles of syrup, &c., can be kept. Access is had to the cooling-chamber by the door a, which is placed in the front of the lower section A. The partition C extends to the front and rear of the section A, but terminates short 50 of the sides thereof, as shown in Fig. 3.

Secured to the ends of partition C adjacent the sides of the section A are the upwardly-

extending walls c c. The walls c c are secured 55 in such a manner that there will be a space between said walls and the inner edges of the adjacent portions of the ledge A'. Within the upper section B are two walls b b, which extend from front to rear thereof and are 60 spaced from the ends thereof. The walls b b do not extend all the way to the top of the section B, and they are secured in such a manner that when the upper section B is secured upon the lower section A of the cooler said 65 walls will rest upon and form a continuation of the ice-chamber walls c c in the section A, thereby forming an air-channel which serves to connect the cooling-chamber and the ice-receptacle. 70

The partition C, which forms the bottom of the ice-chest, is formed with a plurality of apertures therein C', which permit a circulation of air therethrough.

The lower portion of the ice-receptacle, 75 formed by the partition C, the sides of the section A, and the end walls c c, is provided with a lining c², formed of copper or other suitable material. The sides and walls b b of the upper section B of the cooler are also 80 provided with a metallic lining b', which extends a slight distance below the lower edge of said sides and walls, so that it will form an overlapping joint with the upper edges of the walls c c and the side walls of the section 85 A when the two sections of the cooler are assembled.

Secured to the lining c² and extending around each of the apertures c' in the partition C are two open-ended tubes D. The 90 tubes D are made of sufficient height to prevent any water which may accumulate in the ice-receptacle from overflowing the tops thereof and passing down into the cooling-chamber. In order to prevent ice from falling 95 through the tubes when introduced into the ice-receptacle, I provide each tube with a hood E, which fits thereover and rests on the bottom of the ice-receptacle, the tops of the hoods E being made of metal and the sides of 100 metal gauze to permit the passage of air therethrough.

Access is had to the ice-receptacle by means of a door B', which fits in an opening in the front of the upper section B of the cooler. 105 Bolted or secured in any suitable manner to the lower edge of the door B' are a pair of hinge members b², which are adapted to en-

gage with the hinge members b^3 , secured to the front of the top section. The hinge member b^2 has a rounded portion which is adapted to fit in a grooved portion in the hinge member b^3 , from which it will be seen that the door may be readily removed from its opening whenever desired. The door is provided with any suitable form of latch to hold it in its closed position. I also preferably connect the door with the inside of the section B by chains b^4 , which support it in its open position. When in this position, the door acts as a chute upon which the ice is deposited when it is desired to fill the ice-chamber.

15 Placed within the ice-chamber is a battery of coolers F of the usual construction. A pipe f connects the coolers F with a suitable draft-arm secured in the front of the upper section B. Another pipe f' , which passes through the hood E, the cooling-chamber, and through the bottom of the cooler, connects the battery of coolers with a suitable supply of carbonic acid. I have shown two other coolers placed in the ice-receptacles G and H, 20 which are adapted to be connected by the pipes g and h with a suitable supply of aerated water, such as mineral waters and the like. These coolers will also be provided with pipes, which connect them with draft-arms secured 25 in the top section; but as these parts form no part of my invention I have not thought it necessary to illustrate them. The ice-receptacle is also provided with a suitable overflow-pipe K, which passes through the cooling-chamber to any suitable point of discharge.

30 The ledge A' is provided with a plurality of openings a' , extending therethrough and communicating with the ice-chamber.

a' indicates cans which fit the openings a' 35 and are suspended from the ledge A' by having their upper edges flanged to rest thereon. Each of the cans a' is adapted to receive a syrup-jar I, and each of the jars I is provided with a rubber gasket i , which is adapted to 40 overlie the upper edge of the can in order to exclude the warm interior air therefrom.

I do not desire to limit myself to the precise form and construction shown in the drawings, as it is obvious that many minor changes 45 might be made thereto without departing from the spirit of the invention.

Having thus described the invention, what is claimed as new, and desired to be secured by Letters Patent, is—

50 1. In a soda-water apparatus, a lower section, a horizontally-disposed partition secured in said lower section and dividing the same into an ice-receptacle and a cooling-chamber, said partition extending from front to rear but terminating short of the sides of the lower section, upwardly-extending walls secured to the ends of the partition adjacent the sides of the lower section, and an upper section removably secured to said lower sec-

tion, said upper section being provided with 65 two walls secured therein and spaced from the sides thereof and terminating short of the top thereof, said walls being arranged to rest upon the upper edges of the walls of the ice-receptacle in the lower section and form a 70 continuation thereof when the two sections are assembled, as and for the purpose set forth.

2. In a soda-water apparatus, a lower section, a horizontally-disposed partition secured in said lower section and dividing the 75 same into an ice-receptacle and a cooling-chamber, said partition extending from front to rear but terminating short of the sides of the lower section, upwardly-extending walls secured to the ends of the partition adjacent 80 the sides of the lower section, an upper section removably secured to said lower section, said upper section being provided with two walls secured therein and spaced from the sides thereof and terminating short of the top 85 thereof, said walls being arranged to rest upon the upper edges of the walls of the ice-receptacle in the lower section and form a continuation thereof when the two sections are assembled, and a vent-opening in the partition 90 affording a communication between the ice-receptacle and the cooling-chamber.

3. In a soda-water apparatus, a lower section, a horizontally-disposed partition secured in said lower section and dividing the 95 same into an ice-receptacle and a cooling-chamber, said partition extending from front to rear but terminating short of the sides of the lower section, upwardly-extending walls secured to the ends of the partition adjacent 100 the sides of the lower section, an upper section removably secured to said lower section, said upper section being provided with two walls secured therein and spaced from the sides thereof and terminating short of the top 105 thereof, said walls being arranged to rest upon the upper edges of the walls of the ice-receptacle in the lower section and form a continuation thereof when the two sections are assembled, a vent-opening in the partition 110 affording a communication between the ice-receptacle and the cooling-chamber, and an open-ended tube secured around said opening and a hood secured over said tube.

4. In a soda-water apparatus, a lower section, an ice-receptacle arranged therein and spaced from the side walls thereof, an upper section removably secured to the said lower section, said upper section being provided with walls spaced from the sides thereof adapted 115 to rest upon and form a continuation of the ice-receptacle walls, and a passage connecting the space between said walls and the sides of the sections with the ice-receptacle.

5. In a soda-water apparatus, a lower section, an ice-receptacle arranged therein and spaced from the side walls thereof, an upper section removably secured to the said lower

section, said upper section being provided with walls spaced from the sides thereof adapted to rest upon and form a continuation of the ice-receptacle walls, a passage connecting the space between said walls and the sides of the sections with the ice-receptacle, and a passage connecting the ice-receptacle with the lower part of the lower section, whereby

a circulation of air will be permitted over and through the ice in the ice-receptacle. ¹⁰

In testimony whereof I affix my signature in presence of two witnesses.

WILLIAM W. BUTLER.
